UNITED STATES PATENT OFFICE.

STEPHEN PORTER, OF BOSTON, MASSACHUSETTS, ASSIGNOR, BY MESNE ASSIGNMENTS, TO THE EAGLE MANUFACTURING COMPANY, OF MAINE.

METALLIC BRUSH.

SPECIFICATION forming part of Letters Patent No. 396,289, dated January 15, 1889.

Application filed December 21, 1887. Serial No. 258,593. (No model.)

To all whom it may concern:

Be it known that I, STEPHEN PORTER, a citizen of the United States, residing at Boston, in the county of Suffolk and State of Massachusetts, have invented certain new and useful Improvements in Metallic Brushes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in "metallic brushes," so called, in which small wires secured to a flexible piece of material or backing are substituted for animal bristles. This backing, having been studded with these small wires, is then attached to the back of the brush by tacks or other analogous fastening implements.

To conceal the heads of the latter and prevent the hair from catching or becoming entangled therewith, as well as to cover the projecting portion of the flexible material containing the fastening-tacks, and likewise produce an ornate effect, I have disposed exteriorly of and about the wires a continuous metallic ring, plated or otherwise embellished.

My invention relates to the manufacture and peculiar construction of said metallic ring, by which it is readily and easily secured to the back of a brush in such manner as to present a finished and ornamental appearance to the brush as an entirety.

The drawings represent, in Figure 1, a perspective view of a metallic ring embodying my invention. Fig. 2 is a vertical cross-section of a metallic brush with the ring in its final position. Fig. 3 is a side elevation of the back of a brush, showing the fastening attachments secured thereto which engage the ring to hold the latter in place. Fig. 4 represents a modified form in the fastening arrangement.

This invention may be considered as relating to and as an improvement upon a previous invention of mine, (for which I have made application jointly with G. L. Hergert for Letters Patent, filed September 2, 1887, Se-

rial No. 248,616,) which pertains to metallic brushes in which a continuous integral metallic ring provided with a series of fastening-points, also integral therewith, was arranged 55 to fit exteriorly about the wire bristles and cover the fastening implements which are employed to secure upon the back of the brush the flexible material in which said wires are massed. The object of my invention is 60 to cheapen the construction and enable the metallic band to be fastened more quickly in position in the process of manufacture of this class of brushes.

In the drawings, 2 represents the back of 65 a brush made of any suitable material, and to which is secured a piece of flexible or yielding material, 3, in which are inserted and closely massed together a series of small headed wires, 4. A small portion of this elastic material extends beyond the mass of wires and serves to receive the fastening implements, as tacks 5, which are used to unite 70 said material containing the wires to the back of the brush. To retain said fastening-tacks 75 in place, prevent their escape, and at the same time produce a smooth and neat appearance, I have superimposed exteriorly about the mass of wires and over the fastening-tacks 5 a continuous integral metallic 80 ring or band, 6. This ring is struck up from some thin blank sheet of metal, and approximates in shape to the general shape of the mass of wires which it surrounds. In cross-section this ring is cupped or hollow, being 85 concavo-convex, the concave portion being adapted to receive the edge of the flexible material, over which it extends and upon which it rests, thus covering the fastening-tacks 5. Moreover, the rounded or convex exterior surface presents a more ornamental and finished appearance to the article as an entirety. In the process of striking up this continuous integral ring from a blank sheet of metal, I have also formed integral therewith a series of fastening spurs or lips, 7. The latter are continuations of that part of the ring which is contiguous to the back of the brush; but in lieu of being aligned therewith, as in my previous invention above referred to, they are bent at right angles inwardly to the ring at their point of junction 95 100

with the latter. To attach this ring to the back of the brush, I have inserted in the back of the brush a series of fastening staples or eyes, 8, preferably so located that when the 5 ring rests in position on the back of the brush said eyes shall bear against the ring. These fastening devices may be of various shapes and forms, but their function is to engage with the fastening lips or spurs formed 10 integrally on the ring. Furthermore, these fastening devices 8 are positioned on the brush to coincide with the position of the holding-lips 7 on the ring.

In the operation of securing the metallic 15 ring to the back of a brush said ring is first adjusted over the mass of bristles, and the series of lips 7 upon one side are then engaged with the corresponding series of eyes, 8, the ring being held in an oblique position 20 to the back of the brush. The raised side of the ring is then brought down until almost parallel with the back, then by pressure or otherwise it is forcibly sprung outwardly or expanded until the lips 7 are enabled to 25 enter and engage the fastening devices 8, adapted to co-operate with them. As soon as the pressure is removed the inherent elasticity of the metal composing the ring restores the latter to its former proportions, and 30 the lips 7 are held in positive engagement with the fastening devices 8 on the back of the brush. Thus it will be seen that the expense of making the ring is very small, and when the fastening devices, readily inserted 35 mechanically in the back of the brush, are in place the ring can be attached very quickly

and expeditiously. Moreover, after being properly positioned the fastening-tacks 5 are prevented from working loose, dropping out, and escaping.

40

What I claim is—

1. In metallic brushes, a continuous integral metallic ring struck from a blank and provided with a series of fastening-lips, also integral therewith, arranged around its lower 45 edge or contour, said lips being disposed transversely of said edge, substantially as and for the purposes described.

2. In metallic brushes composed of a back portion and a flexible piece of material studed with a massed series of wires attached thereto, a series of fastening devices inserted in said back, combined with a metallic ring having transversely-disposed fastening-lips adapted to engage the fastenings on the 55 brush, substantially as set forth.

3. In metallic brushes, the combination, with the back 2 and the fastenings 8, a massed series of wires, 4, and the flexible material 3 with its fastenings 5, of the integral continuous 60 metallic ring 6, concavo-convex in cross-section, adapted to rest upon the back 2 and overlap the projecting edge of the material 3, and the series of holding-lips 7, integral with and bent transversely of said ring, all co-operating 65 as herein set forth and described.

In testimony whereof I affix my signature in presence of two witnesses.

STEPHEN PORTER.
